CLAIM

The ornamental design for a carrier bag, as shown and described.

DESCRIPTION

1. Carrier bag
- 1.1 : Perspective
- 1.2 : Front
- 1.3 : Back
- 1.4 : Right
- 1.5 : Left
- 1.6 : Top
- 1.7 : Bottom
- 1.8 : Closed top view

The carrier bag consists of an upwardly flared body with two handles shaped like anchor chain links sewn to the main, front and back, sides of the body; An element also in the shape of an anchor chain link is sewn onto the base side of the body; a rigid member shaped like an anchor chain link featuring a cut, so as to resemble a 9, is connected to one end of the top opening or mouth of the body and can be attached with a loop-shaped member fixed to the other end of the top opening or mouth of the body in a closed configuration of the carrier bag.

1 Claim, 8 Drawing Sheets
